UNITED STATES PATENT OFFICE.

HERMANN J. D. WIPF, OF PHILADELPHIA, PENNSYLVANIA, ASSIGNOR TO JOHN WYETH, FRANK H. WYETH, AND EDWARD T. DOBBINS, OF SAME PLACE.

DESIGN FOR A MEASURING-CUP.

SPECIFICATION forming part of Design No. 30,757, dated May 16, 1899.

Application filed April 20, 1899. Serial No. 713,802. Term of patent 14 years.

To all whom it may concern:

Be it known that I, HERMANN J. D. WIPF, a citizen of the United States, residing at the city of Philadelphia, in the county of Philadelphia and State of Pennsylvania, have invented and produced a certain new and original Design for a Measuring-Cup, of which the following is a specification, reference being had to the accompanying drawings, forming 10 part hereof, in which—

Figure 1 is an elevational view of a measuring-cup of the design of my invention. Fig. 2 is a vertical central sectional view through the same, and Fig. 3 is an underneath 15 plan view of the mouth of the cup of my said design. These three views are deemed essential or necessary to fully disclose or illustrate all the features of the design of my said invention.

20 The leading feature of my design consists of the unitary structure made the subject of illustration and having the shape or configuration hereinafter described.

Referring to the drawings, A represents the

cup, of the annular shape or configuration 25 shown, having the slightly-tapering smooth surface interior from the mouth a of the cup to the base a' of the top of the cup A. The exterior surface at the edge of the mouth is rounded into a raised and flat rim c, offset at 30 c' to the annular body c of the cup to near the top, which is offset at d, so as to form a rim e, the exterior of which is rounded, as at f, to the flat surface top g of the cup, as clearly illustrated in Fig. 2 of the drawings. 35

Having thus described my invention, what I claim as new, and desire to secure by Letters Patent, is—

The design for a measuring-cup, substantially as illustrated and herein described. 40

In testimony whereof I have hereunto set my signature in the presence of two subscribing witnesses.

HERMANN J. D. WIPF.
